UNITED STATES PATENT OFFICE.

BERNARD BRETT AND JOHN BRETT, OF COVENTRY, ENGLAND.

DROP-HAMMER.

No. 800,065.

Specification of Letters Patent.

Patented Sept. 19, 1905.

Application filed March 1, 1904. Serial No. 196,094.

To all whom it may concern:

Be it known that we, BERNARD BRETT and JOHN BRETT, subjects of the King of Great Britain, residing at Ashfield House, Counden 5 Road, Coventry, England, have invented certain new and useful Improvements in Drop-Hammers, of which the following is a specification.

This invention relates to improvements in drop-hammers, and refers, primarily, to such hammers that are operated by steam; but part of such improvements may be applied to similar hammers when otherwise operated.

Broadly, its objects are to provide an improved 15 constructive combination of steam-cylinder, cylinder-support, and piston-rod bearing, improved means for taking up the lap of the rope or lifting medium, improved means for forming the guides for the sliding hammer-head and 20 for adjustment of the same, means for connecting the movable guides to the operative valves and for operating the same by the foot or hand of the operator.

These improvements are effected by the 25 mechanism illustrated in the accompanying drawings, in which—

Figure 1 is a general front view of my invention as applied to a steam drop-hammer. Fig. 2 is a side view of the invention. Fig. 3 is an enlarged part-sectional front view of a portion of the piston-rod bearing and of the rope-lifting mechanism. Fig. 4 is an enlarged plan view of those parts shown in Fig. 3. Fig. 5 is an enlarged sectional plan view of one of 35 the guides and its supporting-pillar on line A B. Fig. 6 is an enlarged sectional view of the guide, its supporting-pillar, and the antifriction-roller device for facilitating the free movement of the said guides. Fig. 7 is a detailed plan view of the bracket used to control 40 the movement of the operative valve-rod and communication with the operator's foot movement. Fig. 8 shows modified means to receive the lap of rope.

Similar numbers of reference apply to the same thing or part throughout the several views.

As is well known, such hammers are constructed in some cases with a steam-cylinder 50 mounted upon or about the upper end of the guides which control the movement of the hammer-head. Part of these our improvements refer to the construction and arrangement of such operating parts—that is to say, 55 we provide that the cylinder 12 shall be connected to what may be termed a "distance-

piece" 13, said distance-piece having a suitable base 14, by which it may be bolted to the upper ends of the hammer-guide columns 15 15 or, what is preferable, to a foundation-plate 16, previously secured to such guide-columns in any suitable manner. This distance-piece serves at its one end 13^a as a front cover to the cylinder, with its usual stuffing box and gland at 17. At the other end is 60 formed a bearing 18 for the part-rotative piston-shaft 19, which latter protrudes a little distance beyond said bearing. The exterior of this bearing-part is suitably formed at 65 20 to receive the lap of the lifting rope or band 21, by which the hammer-head 22 is raised, as hereinafter explained. Such a surface may be formed in one with the aforesaid distance-piece or be separately formed and secured thereto. Preferably an extension of such a 70 75 surface is formed as follows: A ring 23 is made, and between the inner surface of such ring and the exterior surface 24 of the bearing are placed antifriction-rollers 25 or the like, so that such ring is very free to rotate. Such 80 a ring is secured from end movement by a suitable flange 26, which is secured to the distance-piece.

Upon the outer end of the shaft 19 is secured the lifting-arm 27, whose outer end is 85 arranged to engage with the lifting rope or band 21. A lifting-rope is usually more convenient than a band, and therefore the apparatus will be described as being constructed therefor. At the outer end of the lifting-arm 90 is formed a bracket 28, which carries an idle pulley 29, over which the lifting-rope is carried from the hammer-head, and thence to a suitable fastening provided at 30 or other convenient place upon the framework or other 95 fixture. Preferably the axis of the idle pulley is at right angles to the piston-shaft. Hence when the arm 27 is part rotated a double lap of rope is carried around and laid upon the exterior surface provided at the end 100 of the distance-piece and which freely unwraps itself when the arm is let go for the fall of the hammer-head. A suitable buffer-stop 31 is provided upon one or both sides to receive the end of the lifting-arm 27 at the 105 limit of its permitted movement.

Referring now to the guides for controlling the movement of the hammer-head, we provide that the main columns 15 15 for such shall be inclined toward each other at the top, thus 110 forming two oppositely-tapered surfaces 32 upon their inner sides. Such columns may

be conveniently made of wrought H iron or other section suitable for the purpose or may be made, of course, of cast-iron. Upon the inner surface of each column we now adjustably secure the guides 33, which are tapered to correspond with the taper of the columns, so that their inner surfaces 34 form parallel lines to each other, such surfaces being prepared to receive the sliding hammer-head 22. These guides 33 are made capable of a rising and lowering movement which may be effected as follows:

The rear side 35 of the guide is planed to slide upon the column 15, and at its upper end it is held thereon by plates 36, suitably pinned to the guide. At its lower end we provide the rollers 37, carried from bearings 38, which are secured to the guide. The said rollers permit an easy movement of the guide. 20 39 represents springs whose upper ends are connected to lugs 40, which latter are secured to the columns 15, while their lower ends are connected to brackets 41, which latter are secured to the guides 33. These springs 25 are made to lift the said guides. Provision is further made by which these guides may be lowered at the will of the operator. This may be done as follows: Brackets 42 are secured to the guides, and from these brackets 30 depend the rods 43, whose lower ends are connected to the treadle-levers 44, to which is attached the treadle-board 45. Hence upon the depression of the board 45 the guides 15 are brought downward, their return movement being effected by the springs 39. The 35 limit of the downward movement of the guides is determined by the adjusting-pins 46, which are rigidly screwed into the guides and freely slide in holes 47, formed in the anvil-block 48 to the extent permitted by the adjusting-nuts 49. A self-adjusting catch-lever such as that shown at 50 may be used, if desired, to keep the treadle-levers down independently of the operator's foot—that is, when the 40 treadle-board 45 is pressed down it is caught and held under the catch part 51 until such time that the operator kicks away the lever and frees the board 45.

50 52 is a rod whose upper end is connected to the steam-valve, and whose end is connected to the starting and stopping lever 53, which is pivoted at 54, the handle of the lever being within easy reach of the operator. This rod 52 passes through the hole 56 in the bracket 42, and upon the said rod are locking-nuts 55, which may be fixed at any desirable position, so that when the bracket 42 is allowed to rise the rod 52 is also raised by coming in contact with the nuts 55, and therefore 55 by the steam is simultaneously cut off, nor can the said rod be lowered in order to open the steam-valve so long as the guides are in their raised position. The lever 53, however, may be used at will, so long as the guides 60 and bracket 42 are in their lowered position.

It will also be noted that by permitting the guides 33 to rise they may be brought so much closer to each other as to clip and hold the hammer-head 22 in any position it may occupy at the moment of the ascent of the said 70 guides. This arrangement is useful during the changing of tools or other similar operations.

Referring once more to the device for receiving the lap of the rope or band 21 under the lifting movement of the arm 27, it will be readily seen that, if preferred, two rings 23^a and 23^b may be used side by side, (see Fig. 8,) so that the doubled rope may dividedly rest one part upon each ring. The device previously shown appears to answer very well, and for this reason: As the lifting-arm 27 is moved, that part of the rope 21 which is given off on the side of the pulley 29, where it is secured at 30, merely lays itself on the 85 surface 20 without any longitudinal movement, whereas the lifting side of the rope is also moving longitudinally, and hence the ring 23 moves with it, and thus prevents any frictional rubbing thereon either in the lifting or lowering process. It will also be readily seen that the arrangement of the adjustable guides and their gripping character may be equally applied to hammer-heads operated by other means than by rope or band, 90 such as piston-rod or lifting-board or the like. 95

What we claim as our invention, and desire to secure by Letters Patent, is—

1. In a drop-hammer, columns converging toward each other at their upper ends, hammer-head guides slidably mounted on the converging surfaces of the columns, means adapted to raise said guides and thereby move them toward each other for clamping a hammer-head in any position throughout their length, 100 means for lowering said guides to move them away from each other to permit the hammer-head to drop, and means to retain the guides in their lowered position.

2. In a drop-hammer, columns converging toward each other at one end, hammer-head-guiding elements slidably mounted on the converging surfaces of the columns, and mechanism to raise and lower said guides to move them toward and from each other to 105 clamp and release a hammer-head.

3. In a drop-hammer, columns converging toward each other at their upper ends, hammer-head guides mounted for sliding motion upon the converging surfaces of the columns, hammer-head-lifting means, means to normally raise said guides toward the top of said columns and thereby move them toward each other for clamping a hammer-head at any point throughout their length, means for lowering said guides to move them away from each other and thereby permit the hammer-head to fall, means to control the operation of said hammer-head-lifting means, and co-operative connections between said controlling 110 115 120 125 130

means and the guides whereby when the guides are raised the operation of said lifting means will be stopped.

4. In a drop-hammer, columns converging toward each other at their upper ends, hammer-head guides mounted for sliding motion upon the converging surfaces of the columns, means tending to maintain said guides in a raised position and thereby draw them toward each other for clamping a hammer-head in any position throughout their length, and means for lowering said guides to move them away from each other and thereby permit the hammer-head to drop.

15 5. In a drop-hammer, columns converging toward each other at their upper ends, hammer-head guides mounted for sliding motion upon the converging surfaces of the columns, means tending to maintain said guides in a raised position and thereby draw them toward each other for clamping a hammer-head in any position throughout their length, and a foot-operated mechanism adapted when operated to lower said guides to move them away from each other and thereby permit the hammer-head to drop.

6. In a drop-hammer, columns converging toward each other at their upper ends, hammer-head guides mounted for sliding motion upon the converging surfaces of the columns, means adapted to raise said guides and thereby move them toward each other for clamping a hammer-head in any position throughout their length, means for lowering said guides to move them away from each other and thereby permit the hammer-head to drop and an adjustable means for limiting the downward movement of the guides.

7. A drop-hammer, comprising a rotative shaft, means for rotating the shaft, a flexible hammer-head-lifting device, a lifting-arm connected to the shaft and adapted to engage said lifting device, and two independent devices upon which said flexible device is adapted to be laid one of which is rotative with respect to the other.

8. In a drop-hammer, a rotatable shaft, means for rotating the shaft, a lifting-arm secured to the shaft and provided with a pulley, a flexible hammer-head-lifting device passing over said pulley and a two-part device adapted to receive said flexible device when the lifting-arm is raised.

9. In a drop-hammer, a rotatable shaft,

means for rotating the shaft, a lifting-arm secured to the shaft and provided with a pulley, a flexible hammer-head-lifting device passing over said pulley and two independent devices upon which said flexible device is adapted to be laid when said lifting-arm is raised, one of said devices being rotative with respect to the other.

10. In a drop-hammer, a prime mover, a rotatable shaft operated by said prime mover, a flexible hammer-head-lifting device, a lifting-arm secured to the shaft and adapted to engage and lift said flexible device, and a distance-piece associated with said prime mover comprising two independent devices upon which said flexible device is adapted to be laid when said lifting-arm is raised, one of said devices being rotative with respect to its companion.

11. In a drop-hammer, a prime mover, a rotatable shaft operated by said prime mover, a flexible hammer-head-lifting device, a lifting-arm secured to the shaft and adapted to engage and lift said flexible device when said shaft is rotated, and a distance-piece associated with said prime mover and forming a bearing for said rotatable shaft, said distance-piece further provided with two independent devices upon which said flexible device is adapted to be laid when said lifting-arm is raised, one of said devices being rotatable with respect to the other.

12. In a drop-hammer, a pair of substantially vertical columns having their adjacent surfaces converging toward one another at one end, a pair of hammer-head-guiding elements, each having one of its faces formed at an angle with respect to its opposite face, the angular face of each of said guiding elements arranged to traverse the inclined face of said columns, and mechanism to move said guides in opposite directions on the converging surfaces of the columns to impart a lateral movement thereto for clamping and releasing a hammer-head.

In testimony whereof we have hereunto set our hands in presence of two subscribing witnesses.
